Primary Examiner — Nathan M Johnston(74) *Attorney, Agent, or Firm* — QuickPatents; Kevin Prince(57) **CLAIM**

The ornamental design for an extendible firearm stand, as shown and described.

DESCRIPTION

FIG. 1 is a front perspective view of an extendible firearm stand, showing my new design in an extended position and in-use in a marsh with a firearm;

FIG. 2 is an enlarged front perspective view thereof in a partially extended position, illustrated without the marsh and the firearm for clarity of illustration;

FIG. 3 is a front perspective view thereof, illustrated in a fully retracted position;

FIG. 4 is a front elevational view of FIG. 3;

FIG. 5 is a rear elevational view of FIG. 3;

FIG. 6 is a left-side elevational view of FIG. 3, the right-side elevational view being a mirror image thereof;

FIG. 7 is a top plan view of FIG. 3;

FIG. 8 is a bottom plan view of FIG. 3; and,

FIG. 9 is an enlarged, partial perspective view thereof, taken along line 9-9 of FIG. 3.

The broken lines in the figures depict environmental matter that forms no part of the claimed design. The dash dot dash broken lines in FIG. 3 are for the purpose of illustrating the enlarged view and form no part of the claimed design.
